UNITED STATES PATENT OFFICE.

LOUIS D. LAWNIN, OF EDWARDSVILLE, ILLINOIS, ASSIGNOR OF ONE-HALF TO N. O. NELSON MANUFACTURING COMPANY, OF ST. LOUIS, MISSOURI, A CORPORATION.

DRINKING-FOUNTAIN.

1,018,572.

Specification of Letters Patent.

Patented Feb. 27, 1912.

Application filed August 27, 1910. Serial No. 579,198.

To all whom it may concern:

Be it known that I, LOUIS D. LAWNIN, a citizen of the United States of America, residing at Edwardsville, county of Madison, 5 and State of Illinois, have invented certain new and useful Improvements in Drinking-Fountains, of which the following is a full, clear, and exact description, reference being had to the accompanying drawings, forming 10 part of this specification.

My invention relates to a drinking fountain and has for its object the production of a drinking fountain that may be very easily attached to or substituted for the ordinary 15 drinking faucets now in common use.

Figure I is a side elevation partly in section showing a drinking fountain embodying the features of my invention. Fig. II is an enlarged top or plan view.

20 In the accompanying drawings:—1 designates a well known type of self-closing faucet such as is now in common use at public drinking places, said faucet being located above a sink 2.

25 3 designates a pipe for supplying water to the faucet 1.

The fountain nozzle 4 is preferably in the form of a ball having a central opening 5, as a nozzle of this shape will be kept absolutely clean by the water discharged 30 through the opening 5. A hollow nozzle holder 6 is arranged below the nozzle and may be secured to it in any suitable manner.

The fountain is supplied with water by a 35 pipe which connects the faucet 1 to the nozzle holder, said pipe being composed of a vertical section 7 having its upper end secured to the faucet, and horizontal sections 8 connecting the vertical section to the nozzle 40 holder.

To enable an authorized person to properly adjust the flow of water at the fountain nozzle, a valve 9 is preferably interposed between the pipe sections 8. This 45 valve is provided with a non-circular adjusting stem 10 adapted to be operated by a key or socket wrench 11.

The L-shaped structure produced by the parts just described is reinforced or supported at its outer end by a rod 12 slidably mounted in a depending leg of the nozzle 50 holder.

zle holder 6, said rod having a hook-shaped end which passes over the top edge of the sink 2. This rod after being properly adjusted may be locked in position by a set 55 screw 13.

A drinking fountain constructed in accordance with this invention can be very easily applied to the public drinking faucets now used, although a simple and inexpensive structure, it is amply reinforced by the rod 12, which may be adjusted to firmly connect the apparatus to sinks of various dimensions.

I claim:—

1. In a device of the character described, the combination with a sink, of a self closing faucet, a fountain nozzle provided with a holder arranged below and secured to said nozzle, said holder having a depending leg, 70 a pipe connecting said faucet to said nozzle holder, and a rod slidably mounted in the depending leg of the nozzle holder, said rod being provided with a curved portion extending over the edge of the sink for supporting said nozzle holder therefrom.

2. In a device of the character described, the combination with a sink or basin of a faucet disposed thereabove, a fountain nozzle suspended from said faucet, and means 80 for reinforcing said fountain nozzle from the sides of said sink or basin.

3. In a device of the character described, the combination with a self-closing faucet, of a fountain nozzle, said nozzle being in 85 the form of a ball provided with a central opening, a nozzle holder arranged below the nozzle and secured thereto, said holder having a depending leg, a pipe for allowing water to pass from the faucet to said nozzle 90 holder, a key-controlled adjustable valve interposed between said faucet and nozzle holder, a rod slidably mounted in the depending leg of the nozzle holder, said rod having a hook-shaped end for the purpose 95 described, and a set screw fitted to the nozzle holder for locking said rod in position.

LOUIS D. LAWNIN.

In the presence of—
GEORGE H. PIERSON,
SAM'L F. LLOYD.
